WILLIAM H. ROSE, OF JERSEY CITY, NEW JERSEY

CONTAINER CLOSURE

Application filed October 24, 1929. Serial No. 402,050.

My invention relates to container closures and refers particularly to container closures adapted to be employed with fiber, wood, or other readily penetrable containers.

5 One of the objects of my invention is a container closure which can be readily and effectively attached to a container by the insertion of prongs, or hooks, carried by the closure member.

10 Another object of my invention is a device of the character described which can be readily removed from its attached position to a container without marring or injuring the container.

15 Another object of my invention is a device of the character described of such mechanical construction that it can be readily manufactured.

20 All of the above mentioned and other desirable and valuable features are possessed by the device of my invention as will be evident upon a consideration of my specification and its accompanying drawings.

25 It is frequently desirable to attach metallic closures, or covers to containers composed of fiber, wood or other readily penetrable materials in such a manner that the closure member may be readily removed without injuring the container.

30 This desirable result is difficult to obtain when the closure comprises a metallic member carrying a plurality of inwardly projecting hooks, or prongs, which are pressed inwardly of the container side during the closed position because it is practically impossible to withdraw the impressed hooks or prongs.

Hence, in cases of this character, it is necessary to exert very considerable force to tear 40 the entire closure member from the container, or to cut the walls of the container below the closure member, both of which processes are highly undesirable.

45 It is for this reason that these otherwise highly efficient closures have not been introduced more largely, as their use has been limited to such containers as are to be completely emptied as soon as opened and which are not to be retained as a storage for the contents.

50 It is evident, therefore, that if a closure of

this character can be so constructed as to have the valuable closure features which are incident to closures of this particular character and at the same time possess the property of being readily removed without marring, 55 or tearing, the container, it would be a great advance in the industry and would enable their much wider adoption.

The device of my invention possesses these valuable attributes and is of such construction as to allow of its production with greater ease and facility than is possible with the present known devices.

The present known devices of this character, as well as my own, are U-shaped, being 65 shaped with an exterior downwardly extended member, the latter carrying the fastening hooks. The container wall is placed between the two parallel elements of the device, the upper edge of the container side 70 supporting the device.

These devices, therefore, have four members positioned angularly to each other, two of the members being in parallel planes spaced but slightly from each other and one 75 of the members carrying a plurality of prongs or hooks. Experience has shown that it is practically impossible to draw a device of this character, or to economically produce it in any other manner and hence their commercialization has been greatly retarded.

I have overcome this difficulty by producing the closure in two separate elements, each 80 readily made, and then combining these two elements.

85 The prongs, or hooks, of these devices are most economically produced by stamping, or cutting, them out of the device itself and then bending them into the desired shape. When hooks of this character are forced into the container side in order to fasten the closure to the container, it is impossible to insert a tool beneath the inserted hooks in order to withdraw them from their holding position, and, hence, they must be forcibly torn 90 from contact with the container, thus ruining the latter.

I have overcome this difficulty by forming an opening around one side, or both sides, of the prong, thus enabling the insertion of a 100

tool beneath the prong to bend it outwardly from its inserted position without tearing or marring the container.

5 The above-mentioned and other, valuable features of my device are clearly described and shown in the accompanying specification.

In the accompanying drawings illustrating modified forms of the device of my invention, similar parts are designated by similar numerals.

10 Figure 1 is a front view of one form of my device attached to a container.

Figure 2 is an enlarged front view of a portion of the device of Figure 1.

15 Figure 3 is a section taken on the line 3—3 of Figure 2.

Figure 4 is a vertical section showing the use of a tool to remove a hook.

20 Figure 5 is a front view of a modified form of my device.

Figure 6 is a section taken on the line 6—6 of Figure 1.

The particular form of the device of my invention shown in Figures 1 to 4, inclusive, 25 comprises a U-shaped container head having the base 10, the upwardly extended side 11 and the outwardly extended flange 12, the latter being capable of abutment upon the upper edge of the side 13 of a container.

30 The outer, or fastening, member of my device comprises the side 14 having the inwardly extended flange 15, the flanges 12 and 15 being attached to each other by spot welding 16, or otherwise.

35 The side 14 carries a plurality of bent fastening means or hooks, 17—18, 17—18, cut out of the side 14, and being outwardly extended before attachment to the container side 13, as shown in dotted lines in Figure 3.

40 There is a cut-out, or opening 19, in the side 14 around each side of the hook element 17.

In operation, my container cover is placed over the upper end of the container, the flange 12 abutting upon the upper edge of the container side 13, the side 18 abutting upon the inner face and the side 14 abutting upon the outer face of the container side 13.

45 The hooks 17—18 are then pressed inwardly, preferably until the face of the hook element 17 is flush with the face of the side 14, thus causing the cover to be firmly affixed, or fastened, to the container and producing a non-leaking jointure therewith.

When it is desired to remove the cover 55 without injuring the container sides, a tool 20 is inserted through an opening 19 and under the hook element 17, and the hook forced outwardly by using the tool 20 as a lever and the side 14 as a fulcrum.

60 In the modified form of my invention shown in Figures 5 and 6, the hooks are of triangular shape 22, 23 and are directed downwardly instead of upwardly.

I prefer to have the hook portion 18 of 65 each tongue positioned above the head base

10, thus giving rigidity to the container side 13 for the better insertion of the hook therein.

The operation of my device is as follows:

The device is placed upon a container side 13 as shown in the drawings, and the hook portion 18 of each tongue is pressed inwardly 70 until it enters the container side 13.

There is thus formed an effective closure for the container.

When access to the container is desired, a 75 tool, as 20, is inserted through an opening 19 and beneath the tongue portion 17, the movement of the tool, using the side 14 as a fulcrum will thus force the tongue outwardly, this action upon each tongue releasing the 80 device from the container without marring the latter.

It will thus be seen that my device is a complete, easily applied container closure easily removed from the container without marring 85 the latter.

I do not limit myself to the particular size, shape, number or arrangement of parts as shown and described as these are given simply as a means for clearly describing the device 90 of my invention.

What I claim is:—

1. In a container closure, in combination, a U-shaped container head; a separate fastening member having a flange fixedly attached to said container head and a side member in a plane parallel to and spaced from said container head; and a plurality of hook shaped tongues carried by said fastening member side, so positioned that each tongue may be moved inwardly through an opening in said fastening member side; said fastening member side having openings through which said tongues may be moved and having an opening upon at least one side of each 100 tongue.

2. In a container closure, in combination, a U-shaped container head having a base, an upwardly extended side and an outwardly extended flange to said side; a fastening member having a flange fixedly attached to said head flange, and a downwardly extended side spaced from and in a plane parallel to said head side, a plurality of hook shaped tongues carried by said fastening member side, said 110 fastening member side having a plurality of openings through each of which the hook portion of a tongue may be passed and inserted within a container side positioned between the two said sides and said fastening member side having an opening upon at least one side of said tongue through which an inserted tool will enable the tongue to be bent outwardly of the device.

3. In a container closure, in combination, 115 a U-shaped container head having a base, an upwardly extended side and an outwardly extended flange to said side; a fastening member having a flange fixedly attached to said head flange and a downwardly extended side 120

125

a

130

spaced from and in a plane parallel to said head side, a plurality of hook shaped tongues cut out of said fastening member side and carried by said fastening member side, said fastening member side having a plurality of openings through each of which the hook portion of a tongue may be passed and inserted within a container side positioned between the two said sides and said fastening member side having an opening upon at least one side of said tongue through which an inserted tool will enable the tongue to be bent outwardly of the device.

4. In a container closure, in combination, 15 a U-shaped container head having a base, an upwardly extended side and an outwardly extended flange to said side; a fastening member having a flange fixedly attached to said head flange, and a downwardly extended side 20 spaced from and in a plane parallel to said head side, a plurality of hook shaped tongues cut out of said fastening member side and carried by said fastening member side, the hook portion of each tongue being positioned 25 above the plane of the container head base, said fastening member side having a plurality of openings through each of which the hook portion of a tongue may be passed and inserted within a container side positioned between 30 the two said sides and said fastening member side having an opening upon at least one side of said tongue through which an inserted tool will enable the tongue to be bent outwardly of the device.

35 Signed at New York city, in the county of New York and State of New York this 22nd day of October, 1929.
